[57] CLAIM

The ornamental design for an integral gauge and fire extinguisher valve housing, as shown and described.

DESCRIPTION

FIG. 1 is a top perspective view of an integral gauge and fire extinguisher valve housing showing our new design;

FIG. 2 is a right side elevational view thereof;

FIG. 3 is a left side elevational view thereof;

FIG. 4 is a top plan view thereof;

FIG. 5 is a bottom plan view thereof;

FIG. 6 is a front elevational view thereof; and,

FIG. 7 is a rear elevational view thereof.

FIG. 1

FIG. 2

FIG. 3

FIG. 4

FIG. 5

FIG. 6

FIG. 7
